G. B. BOSCO

SHORE ADJUSTING TOOL

Filed March 10, 1927

Inventor

Witness:
Carl S. Magnusson

George B. Bosco

UNITED STATES PATENT OFFICE.

GEORGE B. BOSCO, OF CHICAGO, ILLINOIS.

SHORE-ADJUSTING TOOL.

Application filed March 10, 1927. Serial No. 174,196.

The main objects of this invention are to provide an improved tool for accurately adjusting longitudinally of each other, the parts of a shore; to provide a shore adjusting tool which may be readily attached to and removed from the shore so that one such tool may serve a large number of shores; and to provide a tool of this kind which is simple and inexpensive to manufacture, and which is easy and certain in operation so that it may be used by even unskilled labor.

An illustrative embodiment of this invention is shown in the accompanying drawing, 15 wherein:—

Figure 1 is a fragmentary side elevation of a shore to which an improved adjusting tool is applied.

Fig. 2 is a detail in section of the improved tool applied to a strut.

Fig. 3 is an enlarged perspective of the adjusting tool, part of the handle being broken away.

In the specific form herein shown, the improved tool involves the use of a fitting adapted to be supported on one of the struts of a shore and having arranged thereon an operating element or jack located in position to engage the other strut for adjusting 30 the struts longitudinally of each other.

A tool embodying this invention is adapted for use in connection with various forms of overlapping timbers, but, in the construction herein illustrated, the tool is applied to a shore comprising telescoping struts 1 and 2.

The strut 1 may be a post of standard form.

The strut 2 comprises a pair of timbers 3 and 4 arranged in substantially parallel spaced relation on a base 5 and connected together by clamps 6 and 7.

The clamp 6 is the subject of my co-pending application Serial No. 167,697, filed 45 February 12, 1927. This clamp comprises a collar 8 embracing the strut and provided with a keyway 9, in which is seated a wedge 10 adapted to engage one side of the post 1, for holding the struts in their adjusted 50 positions.

In the form shown, the timber 4 projects above the timber 3, and its upper ex-

tremity is provided with a metal cap or bearing plate 11 for engagement with the jacks of the tool.

As illustrated, the improved tool comprises a supporting member in the form of a fitting 12, adapted to embrace the post 1, and on which is mounted an operating element or jack 13. The members 12 and 13 are preferably malleable castings and the fitting 12 is shaped for use with rectangular struts or timbers of standard dimensions.

The fitting 12 includes a pair of arms 14 and 15 disposed in substantially parallel spaced relation to each other for arrangement on opposite sides of the strut 1, and being connected adjacent one end thereof by an integral bearing member 16 arranged to grip another side face of the strut 1. 70 Formed in the arms 14 and 15 adjacent the outer ends thereof, are square apertures 17 arranged to receive a removable locking pin 18, which forms a bearing member adapted to grip the face of the strut 1 opposite the cross piece 16, whereby the fitting grips the post 1 between the members 16 and 18. The pin 18 is removable, so as to permit the fitting 12 to be readily attached to and removed from the shore. To secure the pin 80 against being lost, it is connected to the arm 14 by a short chain 19.

In the form shown, the jack 13 comprises a lever arm 20 provided with trunnions 21 journaled in the fitting 12 and having a cam 85 part 22 located in position to engage the bearing cap 11. The ends of the trunnions 21 are reduced to provide annular shoulders 23, which engage the arms 14 and 15 to secure the jack against lateral shifting in the fitting. To permit the fitting 12 and jack 13 to be readily assembled in the manufacture of the tool, one of the trunnions 21 is journaled in a recess 24 formed in the arm 14. The jack is secured against removal 95 from the fitting by a U-bolt 25 mounted on a flange 26 adjacent the slot 24.

In operation, the fitting 12 is applied to the strut 1, so that by shifting the lever arm 13 in the direction of the arrow, the cam 22 100 engages the bearing cap 11 to raise the post 1. If the shore is not adjusted sufficiently in one operation of the lever arm 13, the fitting 12 may be slid downwardly along the

strut 1 to maintain the cam 22 in operative relation to the cap 11.

The invention being intended to be pointed out in the claims, is not to be limited to or by details of construction of any particular embodiment thereof illustrated by the drawings or hereinbefore described.

I claim:

1. A tool for adjusting a pair of overlapping struts comprising a fitting adapted to embrace one of the struts, a lever pivotally mounted on said fitting, and a cam on said lever adapted to engage an extremity of the other strut for adjusting the struts longitudinally of each other.

2. In a tool for adjusting a pair of overlapping struts, a fitting adapted to embrace one of the struts and comprising a pair of spaced arms, a pair of cross pieces mounted on said arms, one of said pieces being integral with said arms and the other being removable, a lever pivoted on said arms adjacent said fixed cross piece, and a cam on

said lever arranged to abut against an extremity of the other strut.

3. In a device of the class described, a fitting adapted to embrace one of the struts of an adjustable shore, a lever having trunnions pivoted on said fitting, shoulders on said trunnions engaging said fitting to secure said lever against lateral shifting, and a cam on said lever adapted to engage an extremity of the other strut of the shore for adjusting the struts longitudinally of each other.

4. In an adjustable shore, the combination with a pair of overlapping struts, of a fitting detachably secured to one of said struts, a lever having trunnions pivoted on said fitting, one of said trunnions being seated in a slot in said fitting, a flange formed on said fitting adjacent said slot, a U-bolt on said flange and embracing said one trunnion, and a cam on said lever arranged in position to engage the adjacent extremity of the other strut.

GEORGE B. BOSCO.
